UNITED STATES PATENT OFFICE

PAUL A. MEEHAN, OF CLEVELAND, OHIO, ASSIGNOR TO AMERICAN DRESSLER TUNNEL KILNS, INC., OF CLEVELAND, OHIO, A CORPORATION OF NEW YORK

CONTINUOUS-TUNNEL KILN

Application filed July 7, 1928. Serial No. 120,902.

My present invention relates to continuous tunnel kilns and the general object of the invention is to provide improved mechanism for feeding material into and through, and for discharging it from a continuous tunnel kiln. More specifically, the object of the present invention is to provide improved means for moving certain small articles through a tunnel kiln in which they are hardened from an initial condition in which they are so soft and plastic that they must be maintained out of contact with one another to prevent objectionable adherence to one another.

The invention was primarily designed for use in drying and hardening briquette blocks of so-called bituminous amalgam, and the invention comprises a traveling conveyor of novel construction characterized by its capacity for separately holding the great multiplicity of briquette bodies which must be in process of treatment at any one time in order to obtain a kiln capacity suitably large for commercial operation; and the invention is characterized by the adaptability of the conveyor to be charged and discharged in a practically desirable manner. The invention is further characterized by the novel provisions made for mechanically feeding the briquette bodies into the conveyor mechanism as they come from the pug machines in which they are formed.

The various features of novelty which characterize my invention are pointed out with particularity in the claims annexed to and forming a part of this specification. For a better understanding of the invention, however, its advantages and specific objects attained with its use, reference should be had to the accompanying drawings and descriptive matter in which I have illustrated and described preferred embodiments of my invention.

Of the drawings:

Fig. 1 is a diagrammatic plan view of the kiln and material handling mechanism;

Fig. 2 is a diagrammatic elevation in section on the line 2—2 of Fig. 1;

Fig. 3 is a partial section taken similarly to Fig. 2 but on a larger scale;

Fig. 4 is a partial transverse section on the line 4—4 of Fig. 2;

Fig. 5 is a side elevation of a portion of the kiln conveyor mechanism;

Fig. 6 is a partial plan view of the mechanism shown in Fig. 5;

Fig. 7 is a side elevation of a portion of the kiln charging mechanism;

Fig. 8 is a plan view of a portion of the apparatus shown in Fig. 7;

Fig. 9 is a plan view on a larger scale than Fig. 8 of a portion of the conveyor shown in Fig. 8;

Fig. 10 is a perspective view of one form of briquette body which may be handled with the apparatus disclosed.

In the drawings, A represents a continuous tunnel kiln suitable for the intended use. As shown, the kiln structure comprises a kiln chamber A' proper through which the briquette bodies or other ware treated are moved by an endless conveyor B running around a suitable pulley or conveyor wheel C at the discharge end of the kiln chamber and running about upper and lower wheels C' and C' at the inlet end of the kiln. The conveyor B may be driven by any suitable means such as an electric motor C^a driving a worm and wheel or any suitable gear reduction means connected to the shaft C^b of the sprocket wheel C'. The conveyor will preferably be driven very slowly to permit the loading operations to take place. It may be desirable to have the conveyor moving intermittently, the shaft C^b being driven by means of a ratchet wheel and suitable driving means. The upper portion or run of the conveyor passes through the chamber A' while the return portion of the conveyor passes through a subjacent chamber A². The chambers A' and A² are separated by a partition A³. Any usual or suitable means may be employed for heating the ware passing through the kiln chamber A'. As shown, fans D' and D² are provided for circulating a suitably warmed kiln atmosphere through the chamber A'. The atmosphere thus circulated may be heated externally of the kiln in whole or in part or may be heated in whole or in part by contact with the par-

tion A³ which is formed with heating chambers A⁴ in which fuel may be burned in some cases, but with the low kiln chamber temperatures contemplated for the particular use for which the apparatus shown was primarily devised, the partition A³ may be heated by waste heating gases drawn through the chambers A⁴ from adjacent industrial furnaces, (not shown).

10 The conveyor B comprises rollers B' connected by links B² and adapted, as is usual in link conveyors, to engage the pulley wheels C, C', and C², and guide tracks B³. Each successive pair of guide wheels or pulleys B' are connected to a corresponding pair of ware holders b and ba, each pair of ware holders b and ba being rigidly connected together. As shown, the ware holders b and ba are identical in construction and each comprises a 15 perforated back plate b³ and a series of horizontal channel bars b⁴ having their bases secured to the perforated back plate and having their sides upwardly inclined from the horizontal as shown in Fig. 5, in the normal position of the ware supports. Each channel bar forms a ware receiving pocket of a length equal to the width of the conveyor, and the space between each adjacent upper and lower pair of channel bars forms a similar pocket, 20 the bottom wall of each pocket being inclined to the horizontal to prevent the briquette bodies or other ware pieces from falling out of the pocket. The ends of the pockets are closed by angle bars b⁵ and each pair of supports b and ba are rigidly connected by parts b⁶ and b⁷. The bottoms of the channel bar parts b⁴ are formed with perforations in the back plates, the perforations in the channel bars and back plates being provided to permit 25 of a circulation of the kiln atmosphere over the ware pieces received in the ware pockets.

With the described conveyor construction, the ware supports which are vertically disposed as they travel through the chamber A', are horizontally disposed at the entrance end of the kiln as they move vertically from the level of the axis of the wheel C² to the level of the axis of the wheel C'. While the ware supports are thus horizontally disposed 30 they are charged with the ware pieces which they transmit through the kiln. To thus charge the conveyor, I have provided in the construction illustrated, three similar superposed charging mechanisms.

35 Each charging mechanism includes a horizontally movable charging tray. While these trays may be identical in construction and operation I conveniently designate the upper tray D, the intermediate tray DA, and the lower tray DB. The charging mechanisms are so disposed that the tray D charges the first ware support in each group of three successive supports b, ba, b, or ba, b, and ba, while the tray supports DA and DB charge 40 the second and third respectively, of the ware

supports in each such group. Each tray support D, DA, and DB is horizontally movable from the position shown in Fig. 3 in which it extends above a corresponding ware support b or ba, through the spring pressed hinged doors, a, in the end wall of the tunnel kiln, to a position in which it underlies the upper run of a link conveyor E pertaining to the corresponding charge mechanism. Each of the trays D, DA and DB comprises a 45 cellular body formed with cells one for each briquette body or other ware piece, and a sliding bottom D' which advances with the tray from the position of the latter beneath the charging conveyor E into the position shown in Fig. 3 and then is retracted before the tray body is retracted to permit the ware pieces to fall into the ware holding pockets b¹⁰.

50 Each of the trays D, DA and DB receives 55 briquette bodies from a corresponding pug machine F by means of a corresponding charging conveyor E. The three charging units each consisting of a pug machine, conveyor and tray, will preferably be and are 60 shown as similar.

As shown in Figs. 3, 7 and 8, twelve streams of amalgam are extruded from each pug machine F. Each extruded stream which flows continuously from the pug machine is cut 65 into short segments by the corresponding cutting mechanism K, and the separated briquette bodies thereby formed are delivered by means of a corresponding inclined U-shaped slide F' to a specified position on the corresponding charging conveyor E. The slides F' are so disposed with respect to the extrusion face plate of the plug machine F and to the charging conveyor E with which they are associated that the briquette bodies into 70 which the individual streams of amalgam extruded from the various orifices of the face plate are cut, fall onto the corresponding slides F' and are delivered in a horizontal position to the moving conveyor E.

75 Each charging conveyor E is a cellular structure shown in Figs. 7, 8 and 9 as comprising pintles E⁴, links E⁵, connecting adjacent pairs of pintles, and tubular parts E⁶ on the pintles E⁴ spacing the links E⁵ apart so 80 that each adjacent pair of links and the pintles which they connect form a cell receiving a single briquette body. Each conveyor E is 85 of the endless type and constructed with alternate long bottomless sections E' and short 90 sections with bottoms E², all adapted to support briquette bodies. Each conveyor passes over a smooth table G receiving the briquette bodies from the corresponding slides F' while traveling along the table top. Each conveyor 95 E moves transverse to the direction of motion of the corresponding charging tray D which is at a slightly lower level. The table G is arranged with a sliding section G' at the position where the paths of motion of the con- 100

veyor E and the charging tray D cross. When each charging tray is in its retracted position and the long bottomless section E' of the corresponding conveyor E is directly over it, the 5 sliding table section G' is retracted allowing the briquette bodies to drop into the cells of the charging tray.

Each conveyor section E² is constructed of a length corresponding to the movement of the conveyor E during the time when the sliding elements D, D' and G' are performing their sliding movements. Thus the conveyor E will not discharge any briquette bodies until the corresponding charging tray is in position 10 to receive the briquettes. The briquette bodies carried by each conveyor section E² will be either wasted or, which is preferable, returned to the pug machine. It is important that the stream of material leaving the pug 15 machine be continuous once the proper mix 20 of the amalgam has been attained.

Each sliding tray D then moves forwardly together with its corresponding slidable tray bottom D' to a position as shown in Fig. 3 directly 25 over the ware support b or ba. The slidable tray bottom D' is then retracted to permit the briquette bodies to drop into the ware holders b¹⁰. The slidable elements, consisting of the sliding table section G', the 30 charging tray D and the sliding tray bottom D' are operated by suitable mechanism which may comprise separate hydraulic cylinders M one for each sliding element.

It is desirable that the various operating 35 mechanisms for the endless conveyor elements B and E and the sliding elements G', D and D' be synchronized in order that the material to be treated will move in a continuous stream from the pug machines F through 40 the kiln. In order to accomplish the accurate timing and speed control of the various operating mechanism, a central control station from which the operating mechanisms may 45 be simultaneously or independently regulated may be desirable.

The ware supports b and ba on receiving the briquette bodies from the corresponding charging trays are carried by the endless conveyor B into the upper chamber A' of the 50 tunnel kiln as shown in Fig. 2. The briquette bodies in the ware holders b¹⁰ first pass through the portions of the kiln where the kiln temperature is low and in which the water vapor and light oils will be driven off. As 55 the briquettes progress the temperature increases reaching a maximum approaching the discharging position. In the latter stage the briquettes are hardened and some of the smoke producing elements driven off. As 60 shown in Fig. 2, the kiln heating chamber A³ is heated by waste heating gases from adjacent industrial furnaces (not shown), the hot gases being passed into the chamber A³ by the fan D' and exhausted by the fan D². The 65 heating arrangements may be similar to those

shown in my prior application No. 37,077, filed June 15, 1925, in which the air is heated by passing over coils or by coming into contact with the cover plates of fire boxes.

The briquette bodies after passing through the chamber A' are discharged by gravity 70 from the ware holders b¹⁰ after the conveyor B is engaged by the wheel C. The baked briquettes drop into the water seal H where they are cooled. The baffle plate J is supported 75 from the kiln walls and arranged to prevent air entering the discharging portion of the kiln and to deflect the briquette bodies downwardly to the cooling medium H. The bucket conveyor N removes the briquettes 80 when sufficiently cooled so that they are not liable to combustion yet retaining enough heat that when they are discharged from the bucket conveyor they will be in a dry condition. 85

The conveyor B after passing the discharging point moves through the lower chamber A² to the sprocket wheels C² and C'.

In the operation of the apparatus, the several pug machines F deliver the briquette bodies to the corresponding conveyors E, from which they are conveyed by the charging trays D, DA and DB through the small hinged doors, a, of the tunnel kiln to the respective ware supports b and ba. The briquette bodies pass through the chamber A' and after being dried and baked are discharged to the cooling medium, H, and conveyor N. 95

It is apparent to those skilled in the art 100 that my invention is characterized by the novel charging method and apparatus by which a multiplicity of briquette bodies may be handled with very low labor costs and a simplicity of control. It is necessary for the successful commercial operation of apparatus 105 of this type that a great quantity of material continuously be treated under practically automatic conditions of operation.

While in accordance with the provisions of 110 the statutes, I have illustrated and described the best form of embodiment of my invention now known to me, it will be apparent to those skilled in the art that changes may be made in the form of the apparatus disclosed without departing from the spirit of my invention as set forth in the appended claims and 115 that in some cases certain features of my invention may be used to advantage without a corresponding use of other features.

Having now described my invention, what 120 I desire to secure by Letters Patent is:

1. In a briquette plant, in combination, means for forming separate plastic briquette bodies, a kiln, a continuous conveyor for moving said bodies through said kiln, a second 125 conveyor receiving said bodies from said forming means, and means receiving said bodies from said second conveyor and placing said bodies on said continuous conveyor out of contact with one another. 130

2. In combination, a kiln, a continuous conveyor having one run moving horizontally through said kiln and comprising a multiplicity of vertical tray stacks linked together and movable through said kiln in a vertical position, and mechanical means at the inlet of said kiln for charging each tray stack while the latter is horizontally disposed.
3. In a briquette plant, in combination, means for forming separate plastic briquette bodies, a kiln, means for supplying heat to said kiln, a continuous conveyor moving through said kiln, a second conveyor receiving said bodies from said forming means, and tray mechanism at the inlet end of said kiln receiving said bodies from said second conveyor and placing said briquette bodies on said continuous conveyor out of contact with one another.
4. In combination, an elongated kiln, a continuous conveyor passing through said kiln, and ware supports carried by said conveyor each comprising a back plate, a plurality of horizontal channel bars having their bases secured to said back plate and their sides inclined to the horizontal.
5. In a briquette plant, an endless conveyor, ware supports carried by said conveyor, and means for charging said ware supports comprising a series of sliding trays, each tray charging a ware support at predetermined intervals.
6. In a briquette plant, an endless conveyor, ware supports carried by said conveyor, and means for charging said ware supports comprising a sliding tray, a slidable bottom for said tray and means for reciprocating said tray and said bottom.
7. In a bituminous fuel briquette plant, the combination of an extrusion pug machine, with a series of separate troughs receiving the separate streams of amalgam briquettes from said pug machine, and an endless conveyor receiving the briquettes from the troughs and delivering the briquettes to a tunnel kiln.
8. In a briquette plant, the combination of a platform, with an endless conveyor for moving briquette bodies over said platform and consisting of alternate bottomless sections and sections with bottoms, a charging device moving transversely to and underlying the upper run of the conveyor, a slidable platform section between the conveyor and charging device, and means for retracting said platform section when the bottomless section of the conveyor is over the charging device to permit the briquette bodies to drop into the charging device.
9. In a briquette plant, a kiln, an endless conveyor in said kiln, a series of ware supports carried by said conveyor, and means for charging said ware supports comprising a series of superposed slidable charging trays, each tray charging specified ware supports.
10. A briquette plant comprising an extrusion pug machine, an endless conveyor in line with said pug machine adapted to receive plastic briquettes from said machine, a charging conveyor moving transversely to said first mentioned conveyor and adapted to receive material from the latter, a heating kiln, means for receiving material from the charging conveyor, transporting it through said kiln and discharging by gravity to a cooling medium and means for removing the heat treated material from the cooling medium.
11. Apparatus for handling bituminous fuel briquettes comprising a kiln, a ware holder supporting endless conveyor in said kiln, and means for charging the ware holders consisting of a reciprocating charging tray, a slidable bottom for the charging tray moving with said tray over said ware holder and adapted to be retracted to allow the material to drop from said tray into the ware holders.
12. In a briquette plant, the combination with a continuous conveyor having an upper horizontal run portion and a vertical run portion, a multiplicity of vertical ware supports carried in a vertical position by said conveyor, means for transferring material to said ware supports during the vertical run of the conveyor while the former are in a horizontal position and means receiving said material from the conveyor at the end of said horizontal run portion.
13. In a briquette plant, the combination with a kiln, of a continuous conveyor having one side moving through said kiln and comprising a multiplicity of ware supports linked together, and a plurality of charging devices spaced relatively to the ware supports so that the different charging devices are arranged to charge correspondingly spaced ware supports during the same run of the conveyor.
14. In a briquette plant, the combination with a continuous conveyor comprising a multiplicity of ware supports linked together and arranged in successive series, of a plurality of charging devices spaced relatively to the ware supports so that each charging device charges a corresponding ware support in each series.
15. In a briquette plant, the combination of a bottomless conveyor comprising a cellular linked structure, with a series of charging tubes receiving briquettes from a briquette machine and arranged to deliver briquettes in separate streams to the cellular conveyor.
16. In a briquette plant, the combination of a continuous conveyor comprising a cellular linked structure, with means for distributing a plurality of streams of briquettes transversely of said moving conveyor.
17. In a briquette plant, the combination of a continuous conveyor consisting of horizontal and longitudinal series of linked cells, with a plurality of briquette charging tubes arranged to charge each cell with a single briquette.
18. In a briquette plant, a bottomless end-

less conveyor a smooth surface forming a bottom for the upper run of said conveyor, a slidable section of said surface, and means for withdrawing the slidable surface section to allow any material carried by said conveyor to be discharged.

19. In a briquette plant, a multiplicity of linked cells forming a bottomless conveyor, a surface forming a bottom for said conveyor, a series of charging means for distributing briquette bodies to said cells, and a movable section of said bottom forming surface, and means for moving said section to permit the briquettes to be dropped from said bottomless conveyor.

20. The combination of a continuous travelling conveyor comprising spaced apart ware supports and a plurality of charging devices distributed alongside a portion of the conveyor path of travel and separated by spaces greater than the spaces between said supports and operable each to charge a corresponding one of the ware supports in a recurring series of ware supports, each of which series including as many ware supports as there are charging devices.

21. The combination of a continuous travelling conveyor comprising spaced apart separately chargable sections and a plurality of charging devices distributed alongside a portion of the conveyor path of travel and separated by spaces greater than the spaces between said chargeable sections and operable each to charge a corresponding one of the sections in a recurring series of separately chargeable sections, each of which series including as many chargeable sections as there are charging devices.

22. The combination of a continuous travelling conveyor comprising spaced apart ware supports in a vertical run portion of the conveyor and a plurality of charging devices distributed alongside the vertical run portion of the conveyor path of travel and separated by spaces greater than the spaces between said supports and operable each to charge a corresponding one of the ware supports in a recurring series of ware supports, each of which series including as many ware supports as there are charging devices.

Signed at Cleveland, in the county of Cuyahoga, and State of Ohio, this 30th day of June, A. D. 1926.

PAUL A. MEEHAN.
